UNITED STATES PATENT OFFICE.

JACOB JACKSON, OF FORT HOWARD, WISCONSIN.

STOOL FOR TABLES, COUNTERS, &c.

SPECIFICATION forming part of Letters Patent No. 484,719, dated October 18, 1892.

Application filed May 28, 1892. Serial No. 434,739. (No model.)

To all whom it may concern:

Be it known that I, JACOB JACKSON, a citizen of the United States, residing at Fort Howard, in the county of Brown and State of Wisconsin, have invented new and useful Improvements in Stools for Tables, Counters, &c., of which the following is a specification.

My invention relates to an improved table-stool which is equally adapted to serve as a counter-stool; and it has for its object to permit the ready folding of the stool in under the table or against the counter when not in use.

To these ends the invention consists in the features of construction and combination or arrangement of devices hereinafter described and claimed, reference being made to the accompanying drawings, in which—

Figure 1 is a detail vertical sectional elevation showing my invention applied to a table. Fig. 2 is a detail perspective view of the seat, its standard, and the curved supporting-bracket. Fig. 3 is a detail perspective view of the curved supporting-bracket, showing the split or divided socket separated therefrom. Fig. 4 is a detail sectional view of the seat, showing a portion of the bifurcated standard. Fig. 5 is a bottom plan view of the socket-casting which carries the seat, and Fig. 6 is a detail sectional view taken on a line at 30 right angles to that of Fig. 4.

In the embodiment of my invention I provide a curved bracket A, having one end freely let into a two-part or split socket a a', bolted to the under side of the table b, having 35 its lower end about flush with the lower edge of a side piece of the leg-frame to permit said bracket to swing clear thereof in folding the latter under the table. The inner end portion of the seat-bracket A is preferably cylindical, as at a², and has a cross-pin or opposite lateral studs c c, projecting therefrom near its reduced extreme inner end a³, adapted to engage parallel vertical grooves c' c' in the socket a a', while the cylindrical portion a² is 40 adapted to rest in a circular bearing c² in the lower end of the socket to aid, with said extreme inner end a³, engaging a notch or cavity c³ at the bottom of said socket, in holding said bracket in a horizontal position when 45 swung or folded under the table. The upper end of the circular bearing c² communicates with a horizontal annular groove b', formed

in the socket-sections a a' to receive the cross-pin or studs c c, and above the said groove the socket is formed with a recess b² to receive the upper end a³ of the cylindrical portion a² of the bracket A.

B is a forked or bifurcated standard having a sliding connection with the outer end of the bracket A, and its branches or arms B' are provided with inturned meeting toes or lugs d, adapted to be sprung apart when said arms or branches are spread apart by the application of pressure thereto in the required direction, said arms, with their toes or lugs, automatically returning to their original position when pressure is removed therefrom.

To permit the ready connection of the bracket A with the standard B, the arms of the latter are curved or extended laterally, 70 as at B², at their juncture with the foot of said standard, thus providing thereat an enlargement of the slot or space between said arms, into which the end of the bracket is first inserted prior to slipping or passing it 75 upward between said arms in effecting said connection. This enlargement also permits the standard to be turned downward for folding beneath the table or counter.

C is the seat, of suitable construction, having let into and secured to its under side a socket-casting e, whose cavity or socket proper f terminates at its lower end in an approximately-rectangular extension f', whose longitudinal axis is at right angles to the depth of cavity f, and across the lower side of said socket extension e' is a stop e², received between the branches or arms B' of the standard or leg B. It will therefore be seen that by pressing or pulling upward on the seat C, 85 into whose socket or cavity e the upper end of the standard B is inserted, the seat can be 90 swung to one side of said standard for the compact folding of the same with the standard and bracket when swung under the table, 95 out of the way. It will be observed that when the bracket A is projected or swung out from under the table it is locked against swinging or folding vertically, as it would otherwise do, by causing its studs c c to pass into the horizontal groove b', which is effected by moving the bracket vertically until the studs c c register with the groove b' and then turning or 100 rotating the bracket.

To adjust the parts into position for occupying the seat, the end a^3 of the cylindrical portion a^2 is withdrawn from the notch or cavity c^3 , and the bracket is then swung downward on the studs $c c$, after which the bracket is raised until the end a^3 enters the recess b^2 and the studs register with the groove b' , in which said studs are moved out of alignment with the vertical grooves $c' c'$, which movement swings the seat out from beneath the table.

It is obvious that the invention is equally adapted to serve as a counter-stool or in other position.

Having thus described my invention, what I claim is—

1. The combination of a socket-casting, a bracket having a cylindrical portion at one end journaled in the socket and adapted to swing therein at right angles to its axis of rotation, a forked standard having a lengthwise sliding connection with the other end of the bracket and adapted to swing thereupon in the arc of a circle, and means for retaining the bracket in a fixed position when its cylindrical portion is swung in the socket-casting at right angles to the axis of rotation of said cylindrical portion, substantially as described.
2. The combination, with the socket-casting adapted to be secured to a fixture and having vertical grooves, of the bracket having a cylindrical end portion provided with a cross-

pin or lateral studs to engage the vertical grooves in the socket of the casting and a seat having a bifurcated standard which is 35 sliding lengthwise on the bracket, substantially as described.

3. The combination, with the socket-casting having lateral grooves and a cylindrical bearing at its bottom, of the bracket having a cylindrical end portion provided with lateral studs and a reduced extremity to engage said grooves and cylindrical bearing, respectively, a seat, and its standard connected to said bracket, substantially as set forth. 45

4. The combination, with the bifurcated standard having its arms or branches adapted to yield laterally and provided with meeting toes or studs and means for its attachment to a table or other fixture, of a seat having 50 its socket terminating in a rectangular extension whose longitudinal axis is at right angles to the depth of said socket and provided with a stop across its lower side arranged between the laterally-yielding branches of the standard, substantially as described. 55

In testimony whereof I have hereunto set my hand and affixed my seal in presence of two subscribing witnesses.

JACOB JACKSON. [L. S.]
